DESIGN FOR A FOUNTAIN PEN OR SIMILAR ARTICLE

John Hill, Hillside, N. J., assignor to Celluloid Corporation, a corporation of New Jersey

Application November 21, 1936, Serial No. 66,079

Term of patent 7 years

To all whom it may concern:

Be it known that I, John Hill, a subject of the King of England, residing at Hillside, county of Union, State of New Jersey, have invented a new, original, and ornamental Design for a Fountain Pen or Similar Article, of which the following is a specification, reference being had to the accompanying drawing, forming part thereof.

In the accompanying drawing:

The figure is a plan view of a fountain pen showing my new design.

The ornamentation of the fountain pen shown in the drawing comprises alternating vertical

stripes presenting contrasting color effects, one set of vertical stripes being of a plain color and the other set of vertical stripes comprising alternating strata of contrasting colors arranged at an angle. In the latter stripes one set of alternating strata presents differential pearl luster effects and the other set is of a plain color.

I claim:

The ornamental design for a fountain pen or similar article substantially as shown and described.

JOHN HILL.
